UNITED STATES PATENT OFFICE.

ALEXANDER Q. NASH, OF KANSAS CITY, MISSOURI.

OIL-BURNER.

1,225,994.

Specification of Letters Patent. Patented May 15, 1917.

Application filed January 11, 1917. Serial No. 141,877.

To all whom it may concern:

Be it known that I, ALEXANDER Q. NASH, a citizen of the United States, residing at Kansas City, in the county of Jackson and State of Missouri, have invented certain new and useful Improvements in Oil-Burners, of which the following is a full, clear, and exact description, such as will enable others skilled in the art to which it appertains to make and use the same.

The invention relates to oil burners for heating stoves furnaces and the like and seeks to provide a form of burner that will provide means for the economical combustion of the various fuel oils in sufficient quantities to produce an exceedingly large blue flame.

The economical combustion of fuel oils depends upon the complete vaporization of the oils and the uniform mixture in the proper proportions of air with the oil vapor, while the volume of flame produced depends upon the rapidity of the vaporization, and quantity of air that can be uniformly mixed with the oil vapor.

To thoroughly vaporize a large quantity of oil it is essential to bring the oil in direct contact with a sufficiently large surface that is heated to a high temperature, while the uniform mixture of air and oil vapor for perfect combustion can only be accomplished by a rapid and confined movement of the vapor and air at the time of intermingling and for some time after they are associated before issuing to the flame of combustion.

The present invention seeks to provide an improved oil burner for stoves furnaces and the like, that will completely vaporize fuel oils in a regulatable volume and perfectly mingle with the resulting oil vapor a regulatable volume and flow of air.

A further object of the invention is to provide a mixing chamber and a distributing chamber with suitable communication and subject the vapor and air to a rapid movement in the distributing chamber so as to attain a uniform mixture of the vapor and air, and then admit the resulting mixture through the distributing chamber to the flame in a steady and nonagitated flow so that the flame will burn even and constant.

Another object of my invention is to provide a distributing chamber having uniform cross-sectional area throughout its extent, and to provide a burner head of such construction that it may be easily assembled to

form a distributing chamber and a starting trough from two parts.

In the drawings:

Figure 1 is a plan view of the improved oil burner with the orifices in the cap plate not fully detailed.

Fig. 2 is a sectional view taken on line 1-1 of Fig. 1.

Fig. 3 is a perspective view of the air and vaporized oil injecting tube and the air regulating damper.

Fig. 4 is a fragmentary plan view of the lower shell of the burner.

Fig. 5 is a sectional view taken on line 4-4 of Fig. 4.

Fig. 6 is a fragmentary plan view of the perforated division plate which separates the mixing and combustion supply chambers.

Fig. 7 is a sectional view taken on line 1^a-1^a of Fig. 1.

Fig. 8 is a sectional view taken on line 1^b-1^b of Fig. 1.

I will now describe in detail the construction of burner disclosed in the foregoing views.

The lower shell of the burner is circular and approximately flat along the lower wall thereof, from which rises the inner annular flange 16 and the outer annular flange 17, the latter extending outward and forming the radial flange 18, the legs 19 preferably integral with the shell as shown and extending downward as a means of supporting the burner.

The gas and air injecting tube 20 is preferably integral with the lower shell, the end 21 thereof extending within the shell and below the level of the outer radial flange 18, while the end 22 of the injecting tube extends outward from the shell and is preferably rectangular as shown.

The cap plate 23 is also circular and is provided with the orifices 24 extending through the plate for the exit of the combustible mixture of gas and air, and with the outer integral annular flange 25 extending downward and resting on the radial flange 18 between the annularly projecting short flanges 26 formed on the radial flange, the inner integral annular flange 27 extending downward and resting on the lower wall 15, between the short annular flanges 28 which are integral with the lower wall.

The entire cap plate 23 is provided with the orifices 24 the same as that portion thereof to which the latter character numerals are

applied, the same not being shown to avoid the confusion of unnecessary lines in the drawing.

Projecting inwardly from the annular flange 27 are the lugs 29, while corresponding spots 30 are provided on the lower wall 15, the bolts 31 passing through these companion lugs and binding the lower shell and the cap plate rigidly together and forming the circular mixing chamber 32 between the flanges 17 and 27 and the lower wall 15 and the division plate 33, the latter resting on the lower shell at the intersection of flanges 17 and 18.

15 The foregoing construction also forms an unobstructed continuous circular distributing chamber 34 between the flanges 25 and 27 and the division plate 33 and cap plate 23 for the purpose of eliminating all circular movement of the air and gases immediately below the cap plate so that the flame will burn evenly from all orifices 24 along the entire circular face of the cap plate 23.

When the flanges 25 and 27 are placed between the respective flanges 26 and 28 they are preferably set in asbestos or other fire proof paste before tightening the bolts 31 so that the chambers 32 and 34 will be closed to the outer atmosphere and allow no gas or air to escape after entering the injecting tube 20 until reaching the orifices 24.

35 The division plate 33 is provided with the holes 35 so that the air and gases after becoming mixed in the chamber 32 will pass through the holes in a straight upward movement and there will be no circular or agitating movement of the air and gases after entering the chamber 34.

Between the annular flanges 16 and 27 40 and upon the lower wall 15 of the lower shell is formed the generating chamber 36 for the reception of oil or any suitable combustible material for the purpose of generating gas from oil in the pipe 37, the latter beginning at the cut off valve 38 and continuing to the boss 39 integral with the flange 16 and running upward through the boss and then coiling over the chamber and connecting to the cross pipe fitting 40, the 45 valve 41 connecting to the cross, and to the rectangular end 22 of the injecting pipe 20, by the screws 42 passing through the flange 43 integral with the valve, and into the pipe.

50 The regulating valve 41 as shown is the subject of a separate application for Letters Patent filed subsequent to this application and therefore is not fully illustrated or described herein, it is obvious however that the operation of the burner is not restricted 55 to the employment of this particular form of valve.

55 The valve 41 is controlled by the lever 44 and the discharge end 45 of the valve extends sufficiently into the pipe 20 so that 60 when gas is admitted through the valve air

will be drawn through the end 22 of the pipe and the air and gas will be intermingled and associated within the tube 20, the flow of the gas from the valve and drawing the air therearound acting and operating as an injector and forcing the air and gas into and throughout the length of the chamber 32 and maintaining a pressure within the chamber.

70 Pivoted at 46 to the end 22 of the injector pipe 20 is the air regulating damper 47 with 75 the integral arm 48 extending therefrom, the screw 49 being screw threaded into the boss 50 and positioned to open and close the damper by turning the screw to and fro.

80 In operation the trough 36 is supplied with oil which is ignited and the flame therefrom burning upward and around the pipe 37 and vaporizing the oil therein and forming a gas.

85 When the oil in the pipe 37 is sufficiently vaporized the valve 41 is opened allowing the gas to escape therefrom, and as the oil in the pipe is always under pressure, usually from gravity feed, the gas will issue from the discharge end 45 of the valve with considerable force and rapidity expanding and filling the injecting tube 20 and drawing air through the end 22 of the tube and the air and gas are intermingled and associated by the rapid injection through the tube 20, the 90 mixed air and gas traversing and filling the chamber 34, the chamber being circular causing the gas and air to flow continuously entirely and repeatedly throughout the circumference of the chamber and completely 95 mixing the gas and air.

100 The division plate 33 allows the mixed gases to flow through the holes 35 in a vertical direction as a right angle to the direction of circular movement in the chamber 105 32 and thereby prevents this circular movement in the chamber 34 so that the combustible gases will flow to and through the orifices 24 in a steady upward flow and burn in a steady blue flame, the mixture 110 being so perfect and the flow of gases through the orifices so steady that a blue flame will rise uniformly, from the cap plate 23 to a height nearly equal to the diameter of the cap plate when the valves 115 38 and 41 are sufficiently opened and the damper 47 properly regulated.

120 The foregoing construction also allows of regulating the valve 41 to a small opening and the damper 47 to a corresponding opening so that a very small flame will burn evenly from the orifices 24, the burner being adapted to any degree of regulation from the smallest to the largest flame and thereby filling all the requirements of an 125 oil burner for cooking stoves, heating stoves, furnaces and the like.

130 While I have herein described a preferred form of my invention, it is nevertheless to be understood that, in practising the

invention, I may resort to such changes and modifications as fall within the appended claims.

What I claim as new, and desire to secure by Letters Patent, is:—

- 5 1. A burner having an annular distributing chamber of uniform cross-sectional area, means to feed carbureted gas into said distributing chamber at a tangent whereby the gas flows continuously in one direction, and a baffle dividing said chamber into upper and lower annular passages.
- 10 2. A burner having a continuous distributing chamber of uniform cross-sectional area, means to feed carbureted gas into said distributing chamber in a line with the path of flow therethrough whereby the gas flows continuously in one direction, and a baffle dividing said chamber into upper and lower continuous passages.
- 15 3. An oil burner having an annular distributing chamber of uniform cross-sectional area, gas generating means to deliver to said distributing chamber at a tangent whereby the gas flows continuously in one direction, a baffle dividing said chamber into upper and lower annular passages, and means for supplying an oxygenated gas to the burner.
- 20 4. A burner having a continuous annular chamber of uniform cross-sectional area, a perforated baffle dividing said chamber into upper and lower portions, and means to feed carbureted gas into said lower portion in a line with the path of flow therethrough whereby the flow of gas is continuous in one direction.
- 25 5. A burner head comprising a ring like chamber having a starting trough arranged within the ring opening below the zone of combustion, and a retort arranged vertically

over said starting trough and continuous throughout the length of the latter, and means connecting the retort and burner ring to feed gas into the latter at a tangent.

6. A burner head comprising an annular channel of U-shaped cross-section provided with a laterally extending peripheral flange, and an inverted annular member of U-shaped cross-section having one edge resting on said laterally extending flange and the other edge seated within the bend of the first mentioned channel to form a closed distributing chamber and a concentric starting trough.

7. A burner head comprising an annular channel provided with a laterally extending peripheral flange, an inverted channel member of annular form having one edge resting on said flange and the other edge seated within the bend of the first mentioned channel to form a closed distributing chamber and a concentric starting trough.

8. A burner head comprising a channel provided with a laterally extending flange, an inverted channel member having one edge resting on said laterally extending flange and the other edge seated within the bend of the first named channel to form a closed distributing chamber and a starting trough.

9. A burner head comprising a channel provided with a laterally extending flange, an inverted channel member having one edge resting on said laterally extending flange and the other edge seated within the bend of the first named channel to form a closed distributing chamber and a starting trough, and a baffle dividing the said chamber and supported on said flange.

ALEXANDER Q. NASH.
